Jelton P. Polackoff
ATTORNEY

similarly spaced except slot 37 is one and one-half inches from slot 36 and is one full inch in length.

The elastic 22 is inserted through the last slot opening 37 and tacked to the waistband and the strap is then woven in and out of the other six slot openings, the front edge of the strap coming out one inch from the first slot 31.

The male fastener elements 28, 29 and 30 are spaced one-half an inch apart and in line with the female fastener.

When the waist grip straps are snapped on to the first fastener, the waist of the garment becomes one inch smaller; when snapped on the second fastener, two inches smaller; and when snapped on the third fastener, three inches smaller. The surplus material of the garment over the waist divides itself into four sections between the slots and gives a slight draped appearance over the hips. The front and back of the trousers are always smooth.

The modification of the invention illustrated in Figs. 8, 9 and 10 is characterized by the provision of a waist grip strap holding band 50 narrower in width than a waistband piece 51 but constructed the same as the waistband 16 described above so that it can be attached to the waistband of any pair of trousers or waistband garment. In this form, the waistband 50 is fastened on the waist encircling piece 51 at an angle slanting with respect to the longitudinal edges of said waist encircling piece. The straps 18' and the male fasteners 28', 29' and 30' are disposed on a line parallel to the edges of the waistband 50, and the male fasteners are in alignment with the female fasteners 27' on straps 18'. By reason of this construction, the free end of each strap 18' is closer to the upper edge of the waist encircling piece than the opposite end of said strap.

In all other respects, the form shown in Figs. 8 to 10, inclusive, is similar to the form shown in Figs. 1 to 7, inclusive, and similar reference numerals are used to indicate similar parts.

The modification illustrated in Figs. 11 and 12 is characterized by the provision of a band 55 having spaced loops 56 (only one shown) instead of the slot openings shown in the other figures but otherwise the same as the bands shown therein and described above. A strap 57 is also provided which is constructed and arranged identical to straps 18 and 19.

While I have illustrated and described the preferred embodiments of my invention, it is to be understood that

I do not limit myself to the precise constructions herein disclosed and that various changes and modifications may be made within the scope of the invention as defined in the appended claim.

Having thus described my invention, what I claim as new, and desire to secure by United States Letters Patent is:

In a waistband construction for trousers, skirts, waist jackets and other waist fitting garments, a waist encircling piece, a two-part waist encircling band on the inner surface of said piece, the parts of said band disposed in closely spaced end to end relationship and having their adjacent ends secured to the waistpiece at the rear center thereof, said parts sloping upwardly and forwardly of the waist encircling piece from the point of securement thereof, said parts each having spaced openings therealong, a waistgrip strap threaded through the openings in each part of the band, one end of the strap secured to the band at the rear center of the waist encircling piece, said straps sloping upwardly and forwardly from the point of securement thereof, the secured end of the strap being stretchable, a fastener element on the free end of each strap, a plurality of spaced fastening elements secured to the waist encircling band adjacent the free end of each waistgrip strap for engagement with the fastener element on said free end of the respective strap upon stretching of the secured end of the strap, each strap being tunnel-shaped with an open end and a closed end, said stretchable end of the strap constituting the secured end of the tunnel and a stiffener member secured inside the closed end of each tunnel, the fastening elements on the waist encircling band disposed on a line slanting with respect to the longitudinal edges of the waist encircling piece substantially in line with the longitudinal axis of the adjacent waistgrip strap so that the free end of the strap is closer to the upper edge of the waist encircling piece than the opposite end thereof.
